(57) **CLAIM**

The ornamental design for indoor amusement ride, as shown and described.

DESCRIPTION

FIG. 1 is a front left isometric view of an indoor amusement ride.

FIG. 2 is a back left isometric view thereof.

FIG. 3 front right isometric view thereof.

FIG. 4 is a back right isometric view thereof.

FIG. 5 is a front side elevation view thereof.

FIG. 6 is a back side elevation view thereof.

FIG. 7 is a left side elevation view thereof.

FIG. 8 is a right side elevation view thereof.

FIG. 9 is a plan view thereof, with the rider carriages in one position in the open space and viewing platforms in a first position.

FIG. 10 is a plan view thereof, with the rider carriages moved in the open space and there viewing platforms rotated to a second position. The rider carriages may move about the open space and the viewing platforms can fully rotate to any given position.

FIG. 11 is a cross sectional view of the cross section indicated by line FIG. 11-FIG. 11 in FIG. 6.

FIG. 12 is a cross sectional view of the cross section indicated by line FIG. 12-FIG. 12 in FIG. 6.

FIG. 13 is a cross sectional view of the cross section indicated by line FIG. 13-FIG. 13 in FIG. 7; and,

FIG. 14 is a cross sectional view of the cross section indicated by line FIG. 14-FIG. 14 in FIG. 7.

The features shown in dash-dot lines in the drawing depict portions of the indoor amusement ride. The dash dot dash lines define the bounds of the claimed design. The broken lines form no part of the claimed design.
